US00D803839S

(12) **United States Design Patent** (10) **Patent No.:** **US D803,839 S**
(45) **Date of Patent:** **** Nov. 28, 2017**

(54) **CONNECTOR FOR ELECTRONIC DEVICE**

(71) Applicant: **ZEROPLUS TECHNOLOGY CO., LTD.**, New Taipei (TW)

(72) Inventor: **Chih-Ying Lin**, New Taipei (TW)

(73) Assignee: **ZEROPLUS TECHNOLOGY CO., LTD.**, New Taipei (TW)

(**) Term: **15 Years**

(21) Appl. No.: **29/571,241**

(22) Filed: **Jul. 15, 2016**

(51) LOC (10) Cl. **14-02**

(52) U.S. Cl.

USPC **D14/433**

(58) **Field of Classification Search**

USPC D14/356, 432-434, 453, 454, 511, 203.8, D14/209.1, 238.1, 240, 125; 439/638, 439/928, 105, 502; 710/303, 304; 361/679.41, 679.55, 679.56; D13/110, D13/133, 146

CPC G06Q 20/202; G06Q 20/322; G06Q 20/32; G06Q 20/20; G06Q 20/327

See application file for complete search history.

(57) **CLAIM**

The ornamental design for a connector for an electronic device, as shown and described herein.

DESCRIPTION

FIG. 1 is a perspective view of the connector;
FIG. 2 is a front view of the connector;
FIG. 3 is a rear view of the connector;
FIG. 4 is a left side view of the connector;
FIG. 5 is a right side view of the connector;
FIG. 6 is a top view of the connector; and,
FIG. 7 is a bottom view of the connector.

1 Claim, 7 Drawing Sheets

FIG. 1

FIG. 2

FIG. 3

FIG. 4

FIG. 5

FIG. 6

FIG. 7
